DESIGN FOR A DISPLAY STAND FOR JEWELRY AND SIMILAR ARTICLE

Rudolf Christen, Buffalo, N. Y.

Application January 29, 1937, Serial No. 67,336

Term of patent 3½ years

To all whom it may concern:

Be it known that I, Rudolf Christen, a citizen of the United States, residing at Buffalo, Erie County, State of New York, have invented a new, original, and ornamental Design for a Display Stand for Jewelry and Similar Article, of which the following is a specification, reference being had to the accompanying drawing, forming a part thereof.

In said drawing:

Fig. 1 is a perspective view of the display stand for jewelry and similar article showing my new design.

Fig. 2 is a side elevation of the same.

Fig. 3 is a rear elevation of the same, and

Fig. 4 is a sectional elevation of the same, the section being taken approximately along the line 4—4, of Fig. 1.

I claim:

The ornamental design for a display stand for jewelry and similar article, as shown.

RUDOLF CHRISTEN.
